UNITED STATES PATENT OFFICE.

LOUIS W. RICE, OF NEW YORK, N. Y., ASSIGNOR TO BERNARD RICE'S SONS, INC.,
OF NEW YORK, N. Y., A CORPORATION OF NEW YORK.

DESIGN FOR A HAND MIRROR OR SIMILAR ARTICLE.

Application filed March 23, 1928. Serial No. 25,982. Term of patent 7 years.

To all whom it may concern:

Be it known that I, LOUIS W. RICE, a citizen of the United States, residing at 325 Fifth Avenue, New York city, in the county of New York and State of New York, have invented a new, original, and ornamental Design for a Hand Mirror or Similar Article, of which the following is a specification, reference being had to the accompanying drawing, forming part thereof.

Fig. 1 is a plan view of the hand mirror or similar article, and Fig. 2 is a side view of the same.

The dominant feature of my design resides in the contour of the back and the arrangement of the lines thereon for ornamental effect.

I claim:

The ornamental design for a hand mirror or similar article substantially as shown and described.

LOUIS W. RICE
